UNITED STATES PATENT OFFICE.

PHILIP WALLIN, OF CANTON, OHIO, ASSIGNOR TO THE TIMKEN ROLLER BEARING COMPANY, OF CANTON, OHIO, A CORPORATION OF OHIO.

TAPER-GAUGING MACHINE.

Application filed August 4, 1926. Serial No. 127,060.

My invention relates to taper gauging machines and has for its principal object a simple and accurate means for automatically gauging the taper of such articles as 5 taper rolls for roller bearings. The invention consists in a taper gauging device that can be incorporated in a machine for gauging the sizes of such rolls. The invention consists principally in an adjustable housing 10 in which is mounted a taper gauging mechanism that is able to accommodate itself to different sizes of rolls. The invention further consists in the gauging machine and in the parts and combinations of parts hereinafter described and claimed.

In the accompanying drawing, wherein like numerals indicate like parts wherever they occur,

Fig. 1 is a top plan view of a gauging machine embodying my invention,

Fig. 2 is a part vertical sectional view thereof,

Fig. 3 is a cross sectional view on the line 3—3 in Fig. 2,

Fig. 4 is a cross sectional view on the line 4—4 in Fig. 2,

Fig. 5 is an end elevation; and

Fig. 6 is a vertical sectional view on the line 6—6 in Fig. 2.

30 A housing 1 is provided with a bore 2 whereby it is mounted on an upstanding column 3 on a suitable base 4. Extending through another bore 5 in said housing 1 is a rod 6 that is provided with an enlarged 35 end portion 7 having a knurled head 8 and with a shoulder 9 at the lower end whereby it is held in the housing 1. Said rod 6 has a threaded lower end 10 fitting in a threaded hole in the base 4. Thus the housing 1 40 may be raised or lowered by turning said rod 6. Extending through an elongated slot 11 in said housing 1 into the column 3 is a locking screw 12 that is provided with an operating arm 13. Thus the housing 1 45 may be held in any desired position on the column 3 by turning said locking screw 12 to clamp the housing 1 on the column 3.

50 The housing 1 is provided with an enlarged bore 14 parallel with the column 3, in which bore 14 is slidably mounted a hollow casing or slide 15 that is normally held in its lowermost position in the housing by means of springs 16 secured to the enlarged

head 17 of the casing 15 and to the housing 55 1. A pin 18 projects from the housing into a slot 19 provided therefor in said casing or slide, so as to prevent rotary movement of the slide. Said slide 15 carries the gauging mechanism hereinafter described; and 60 since said slide is yieldable in the housing as above described, it can accommodate itself to different sizes of work.

Mounted so as to rock on a pin 20 in the slide is a gauging block 21 that is provided with an upwardly extending projection 22 in whose top is formed a V-shaped recess 23. In this recess 23 rests a knife edge 24 formed in the middle of the lower surface of a rock shaft 25. The outer ends 70 of the upper surface of said rock shaft 25 are provided with aligned knife edges 26 each of which is received in an inverted V-shaped depression 27 formed in a block 28 that is fastened at the end to a flat spring 75 29. Said springs 29 are secured to a bracket 30 as by screws 31, which bracket 30 is secured to the slide 15 as hereinafter described. By the construction just described, the rock shaft 25 is held between the gauging block 21 and said hold-down blocks 28.

80 A contact arm 32 extending through said hollow slide 15 is provided with forked ends 33 that are secured to said rock shaft 25, as by taper pins 34. Mounted on a cap 85 35 of insulating material in the upper end of the slide 15 is a block 36 that is provided with upstanding portions 37 to each of which is secured a contact member 38 of spring metal. The contact points 39 of said 90 contact members 38 are adapted to contact respectively with contact screws 40 mounted on a block 41 of electric conducting material secured to said cap 35 as by screws 42. The block 36 that carries said contact 95 springs 38 is connected to a battery or other source of electric current (not shown in the drawings).

100 The upper end of the contact arm 32 consists of a pin 43 of some non-conducting material, said pin extending between the ends of said contact springs 38. Interposed between said contact springs 38 near their contact ends is a pin 44 of non-conducting material that is of the same diameter as the 105 pin 43 of the contact arm 32 and is secured to the block 41. Thus the ends of the contact springs 38 normally rest against said

anchor pin 44, and said contact springs 38 normally hold the pin 43 and contact arm 32 in neutral position; but when the gauging block 21 is tilted in either direction by an off-taper roll, the contact arm 32 will likewise be tilted and the contact point 39 of one of the contact springs 38 caused to contact with a contact screw 40. This will result in the closing of an electric circuit and in the operation of any suitable ejecting mechanism (not shown in the drawings) for ejecting rolls that are off-taper.

In order to permit adjustment of the V-blocks 28 to place the rock shaft 25 and contact arm 32 in zero or neutral position the bracket 30 from which said blocks 28 are supported is secured to a protecting portion 45 of the slide, as by a screw 46. Interposed between the inner surface of the bracket 30 and said projecting portion 45 of the slide 15 are springs 47. Said projecting portion 45 of the slide 15 is shown as a separate member, secured to the slide by screws 48.

A suitable device 49 (which may be of any well known construction and is indicated diagrammatically, is provided for moving the taper rolls 50 along a suitable track 51 or the like, to bring them, one at a time, under the gauging block 21. If the roll 50 is of exactly the desired taper, there will be no movement of the gauging block 21 or of the contact arm 32; but if the roll is off taper, the gauging block will be tilted, thus rocking the rock shaft 25 and causing the contact arm 32 to be tilted. If the variation from the correct taper is great enough, one of the contact springs 38 will be caused to contact with a contact screw 40, thus closing an electric circuit and operating an ejecting mechanism. Obviously the limits of tolerance may be varied by adjusting the positions of the contact screws 40.

The device shows both sets of contact screws 40 and contact springs 38 connected up in a single ejecting circuit; but obviously two different circuits and ejecting devices might be provided, thus separating rolls having too much taper from those having too little taper.

The above described device may be incorporated in any of the well known types of machines for sorting taper rollers according to their size, the taper gauging mechanism being made a station of the gauging machine operating prior to the first size gauge. The device is simple and easy to operate, there are few moving parts to get out of order and the device is very accurate. Obviously numerous changes might be made without departing from the invention and I do not wish to be limited to the construction shown.

What I claim is:

1. A device of the kind described comprising a housing, a slide yieldably mounted

therein and taper gauging mechanism carried by said slide, whereby said taper gauging mechanism is adapted to gauge the taper of different sizes of work.

2. A device of the kind described comprising a yieldably supported casing, a gauging block pivotally mounted in said casing and having a V-shaped depression, a rock shaft having a knife edge portion resting in said V-shaped depression, said rock shaft having knife edge portions along the side opposite said first knife edge, spring pressed blocks having V-shaped depressions in which said second knife edge portions are received and a contact arm secured to said rock shaft to swing therewith when said gauging block is engaged by work of incorrect taper.

3. A device of the kind described comprising a yieldably supporting casing, a gauging block pivotally mounted in said casing and having a V-shaped depression, a rock shaft having a knife edge portion resting in said V-shaped depression, said rock shaft having knife edge portions along the side opposite said first knife edge, spring pressed blocks having V-shaped depressions in which said second knife edge portions are received a contact arm secured to said rock shaft to swing therewith when said gauging block is engaged by work of incorrect taper, and contact members adapted and arranged to be engaged by said contact arm.

4. A device of the kind described comprising a yieldably supported casing, a gauging block pivotally mounted in said casing and having a V-shaped depression, a rock shaft having a knife edge portion resting in said V-shaped depression, said rock shaft having knife edge portions along the side opposite said first knife edge, spring pressed blocks having V-shaped depressions in which said second knife edge portions are received, a contact arm secured to said rock shaft to swing therewith when said gauging block is engaged by work of incorrect taper, and contact members disposed on either side of said contact arm to be operated thereby.

5. A device of the kind described comprising a base having an upstanding column, a housing having a bore by which it is mounted on said column, a casing slideable in a bore provided therefor in said housing, springs secured to said casing and to said housing to hold said casing in said housing, a gauging block pivotally mounted in said housing and having a V-shaped depression therein, blocks spaced from said gauging block and each having a V-shaped depression therein, a rock shaft interposed between said gauging block and the blocks having said V-shaped depressions and having knife edges resting in the depressions thereof, a contact arm secured to said rock shaft and extending through said casing, contact members mounted at the end of said casing and

having contact points thereon, said contact arm having a portion extending between said contact members and contact screws adapted to be engaged by the contact points of said contact springs when said contact arm is swung.

6. A device of the kind described comprising a base having an upstanding column, a housing having a bore by which it is mounted on said column and also having a second bore, a casing slideable in said second bore in said housing, springs secured to said casing and to said housing to hold said casing in said housing, a gauging block pivotally mounted in said housing and having a V-shaped depression therein, a bracket adjustably secured to said housing, flat spring arms secured to said bracket and extending into said casing, a block secured to the end of each spring arm and having a V-shaped depression therein, a rock shaft interposed between said gauging block and the blocks having said V-shaped depressions and having knife edges resting in the depressions thereof, a contact arm secured to said rock shaft and extending through said casing, contact members mounted at the end of said casing and having contact points thereon, said contact arm having a portion extending between said contact members and contact screws adapted to be engaged by the contact points of said contact springs when said contact arm is swung.

7. A device of the kind described comprising a base having an upstanding column, a housing having a bore by which it is mounted on said column, a casing slideable in a bore provided therefor in said housing, springs secured to said casing and to said housing to hold said casing in said housing, a gauging block pivotally mounted in said housing and having a V-shaped depression therein, a bracket secured to said housing, flat spring arms secured to said bracket and extending into said casing, a block secured to the end of each spring arm and having a V-shaped depression therein, a rock shaft interposed between said gauging block and the blocks having said V-shaped depressions and having knife edges resting in the depressions thereof, a contact arm secured to said rock shaft and extending through said casing, contact springs mounted at the end of said casing and having contact points thereon, said contact arm having a portion extending between said contact springs, an anchor pin located between the ends of said contact springs, and contact screws adapted to be engaged by the contact members of said contact springs when said contact arm is swung.

8. A device of the kind described comprising a base having an upstanding column, a housing having a bore by which it is mounted on said column, a rod held against longitudinal movement in said housing and rotatable therein, said rod having a screw threaded lower end extending into a threaded hole in said base, whereby the housing may be raised and lowered on said column, a locking device for locking said housing on the column, a casing slideable in a bore provided therefor in said housing, springs secured to said casing and to said housing to hold said casing in said housing, a gauging block pivotally mounted in said housing and having a V-shaped depression therein, a bracket adjustably secured to said housing, flat spring arms secured to said bracket and extending into said casing, a block secured to the end of each spring arm and having a V-shaped depression therein, a rock shaft interposed between said gauging block and the blocks having said V-shaped depressions and having knife edges cooperating with the depressions thereof, a contact arm secured to said rock shaft and extending through said casing, contact springs mounted at the end of said casing and having contact members thereon, said contact arm having a portion extending between said contact springs, an anchor pin located between the ends of said contact springs, and contact screws adapted to be engaged by the contact members of said contact springs when said contact arm is swung.

9. A device of the kind described comprising a casing that is yieldably supported whereby it may accommodate different sizes of work, a gauging block pivotally mounted in said casing, an arm, and means operatively connecting said arm and said gauging block, whereby said arm is swung when said gauging block is engaged by work of incorrect taper.

10. A device of the kind described comprising a casing that is yieldably supported whereby it may accommodate different sizes of work, a gauging block pivotally mounted in said casing, spring pressed blocks spaced from said gauging block and a rock shaft interposed between said gauging block and said spring pressed blocks.

Signed at Canton, Ohio, this 30th day of July, 1926.

PHILIP WALLIN.
